METHOD OF CORRUGATING OR FOLDING TUBES.

1,120,267.

Specification of Letters Patent.

Patented Dec. 8, 1914.

Application filed January 11, 1913. Serial No. 741,387.

To all whom it may concern:

Be it known that I, LOUIS H. BRINKMAN, a citizen of the United States, and a resident of Glen Ridge, county of Essex, State 5 of New Jersey, have invented certain new and useful Improvements in Methods of Corrugating or Folding Tubes, of which the following is a specification.

My invention relates to corrugating tubes 10 helically, and the invention consists in the method of corrugating or folding tubes helically, as hereinafter explained and more particularly pointed out in the appended claims.

Various methods and apparatus have been 15 proposed for corrugating tubes helically, in an attempt to form helically corrugated tubes with deep folds to provide the flexibility or relatively great radiating surface necessary 20 to the adaptation of such tubes to extensive fields of use such, for example, as for flexible connections, couplings, radiators, etc., but the methods and apparatus proposed for making such tubing either stretch or crush 25 and stretch the metal into folds without twisting the metal, and this twisting I have found to be essential in deeply corrugating tubing. The methods and apparatus which have been proposed are such that the deeply 30 corrugated tubes desired can not be commercially manufactured, and so far as I am aware, heretofore it has been impossible to commercially manufacture corrugated tubes with folds or corrugations of such depth as 35 to render the tubes really flexible, and provide a relatively great radiating surface.

By the use of my invention helically corrugated tubes of considerable length may be 40 readily made, the length of the corrugated tube being limited only by the length of the tube to be corrugated, and the corrugations or folds may be of extreme depth so as to provide a tube of great flexibility and relatively large radiating surface.

In carrying out my invention, the metal 45 of the tube is folded in such a manner that it is not wrinkled or materially thickened or spun out during the folding process, and in practicing the preferred form of the invention, the wall thickness of the tube remains substantially unchanged during the 50 folding process.

These results are made possible by twisting the metal of the tube, and while twisting it pressing upon it along a helical line 55 along which the metal will fold, the pressure being exerted upon the wall of the tube at a progressively shifting short portion thereof and the actual twisting of the metal being localized to substantially the short portion 60 of the tube being pressed upon or the short portion being folded, so that the portion of the tube which has been folded to the desired final form is protected from distortion by the twisting force. The twisting 65 of itself tends to fold the tube by distorting it helically and contracting it longitudinally, and thus greatly reduces the pressure required on the metal to deepen the folds, and if continued after the folds are thus formed, 70 it reduces the pitch of the folds and increases their depth by continuously forcing the folds around helically analogous to the manner in which a helical spring of a certain pitch and diameter may be reduced in 75 diameter and pitch by slipping it over a rod to prevent buckling, and holding one end down on the rod while twisting the rod and holding the opposite end of the spring from rotation, while permitting it to 80 move along the rod.

In deeply corrugating tubing, I have found that it is of great importance, if not essential, to apply the pressure along the helical line inwardly against the wall of the 85 tube. When the pressure is exerted from the outside inwardly on the tube to form the folds by displacing the metal inwardly, the diameter of the pressed-in metal is less than that of the original tube; hence there 90 is more than sufficient metal for the circumferential measurement of the folds and the metal does not have to be stretched or spun out in forming the folds as would be the case if the pressure was exerted from the 95 inside outwardly. The metal is crowded in as it is pressed inwardly, producing what without the twisting of the metal would be an excess of metal along the helical line of pressure, such as takes place when it is attempted to force the metal of a hollow cylinder or tube inwardly at any point along its length to reduce the diameter at that point; in which event, by being crowded in along 100

the line of reduced diameter, the metal is caused to wrinkle or pucker. This crowding of the metal would soon limit the depth of the folds if it were not for the twisting force above mentioned; but by producing a twisting force in the tube to actually twist the metal, and while the tube is under such force, pressing inwardly on it along a helical line, the excess metal is displaced helically as it is being forced inwardly so as to keep the wall substantially uniform in thickness during the folding process, permitting the formation of folds of great depth.

The resistance of the metal of a tube to inward pressure is so great that sufficient friction between the corrugating tool and the metal is produced to twist the tube, and because of this resistance the metal can be gripped and drawn together along the length of the tube to form the axial sectional configuration of the folds and otherwise formed into the desired shape without appreciable stretching or spinning of the metal.

In corrugating tubes according to the more preferred form of my invention, I initiate a helical groove in the tube of such pitch as to mark out along the tube sufficient metal to form an ultimate fold of the desired depth and pitch without substantial change in wall thickness, and progressively increase the depth of the groove and decrease its pitch by simultaneously pressing inwardly on the metal along the groove, drawing together its convolutions and twisting. By marking out along the tube substantially enough metal to form the ultimate fold of the desired depth and pitch, sufficient metal is provided to form the fold without having to spin or stretch from a less amount of metal a sufficient length to form the axial sectional configuration of the fold. This feature and the twisting permit the tube to be folded or corrugated without substantially changing its wall thickness. By pressing on the folds while they are being formed, they may be made to assume different desired cross-sectional configurations, depending upon the angle at which the pressure is exerted upon them.

In corrugating tubes according to the preferred manner of practicing my invention, I rotate the forward end of the tube at a certain speed and rotate the rear end of the tube at a less speed, and groove it at a speed having a definite relation thereto, the ratio between the speeds being constant so as to produce a positive and constant twisting force in the tube to produce uniform corrugations or folds in the finished tube; and when desired, I bend the folds longitudinally toward one end of the tube while they are being formed. In order to limit the pitch of the ultimate folds and their depth, and to hold the tube from buckling

during the folding or corrugating process, or, in other words, to localize the twisting of the metal substantially to the progressively shifting short length of the tube being pressed upon or to the progressively shifting short length being folded. I provide an inner support upon which the tube is folded. With this inner support the inward pressure may be progressively applied by the tool until the depth of the groove in the tube is positively limited by coming in contact with the support, whereupon, if there should be any irregularities or unevenness in the metal of the groove, the tool will act to smooth or iron out any unevenness in the metal.

The actual twisting of the metal is not limited strictly to that portion of the tube being pressed upon by the tool or within the tool, for the tool in most cases will not bring the metal down upon the inner support with sufficient friction to prevent the metal of the folds as they leave the tool from being twisted until they are brought down on the support. In some cases the folds as they leave the tool may not even touch the mandrel, and therefore the last few folds adjacent the mandrel will also be twisted to bring them firmly down upon the mandrel or inner support. When, therefore, I refer to the actual twisting being localized to the portion of the tube being pressed upon or gripped, I wish to be understood as meaning not only the portion of the metal immediately within the tool, but also the few folds adjacent the tool which have not yet been brought down with sufficient friction upon the inner support to prevent further twisting.

In order to prevent distortion or mutilation of the forward end of the tube in starting the corrugations under the powerful twisting force necessary, I first draw down the end of the tube to form a tapering portion the small end being of such diameter as to fit upon the inner support. In pressing upon the tube I commence at the point where the tube diverges from the inner support, so that the tube is from the start forced into firm engagement with the inner support to prevent its distortion.

My invention will be more readily understood and further objects of the invention will more fully appear from the following description taken in connection with the accompanying drawings showing the preferred form of apparatus for carrying out the process, in which—

Figure 1 is a front elevation of the machine, showing a tube in process of corrugation; Fig. 2 is an enlarged view of a part of the mechanism showing the corrugating tool or die partly in section and in position to commence corrugating the tube; Fig. 3 is a view showing the die and a part of the

corrugated tube in section; Fig. 4 is a cross-sectional view of the die shown in Fig. 2, taken on line A—A and looking in the direction of the arrows B; Fig. 5 is a fragmentary sectional view showing a modified form of corrugating die in process of operation; Figs. 6, 7, 8 and 9 show different forms of tube corrugated by said machine; Fig. 10 illustrates the manner in which the metal of the tube is twisted or carried around helically as it is being compressed; and Fig. 11 is a diagrammatic illustration.

Referring to the drawings, Fig. 1 is a front elevation of a suitable machine frame 1 having a head stock 2 and a tail stock 3. 4 is a shaft journaled in the head stock 2 and counter pillow block 5 and driven through any suitable means such as pulley 6. The inner end of the shaft is provided with a chuck 7 (Fig. 2) to which is secured the tube 8 to be corrugated or folded, and also an inner support or mandrel 9 which extends through the tube, the tube and mandrel being secured to the chuck by any suitable means such as set bolts 10, 10', so that they will revolve together with the chuck. A carriage 11 of suitable construction is slidingly mounted on the frame 1 and is moved longitudinally along the same by means of a screw spindle 12 journaled in the head and tail stocks and driven from shaft 4 through suitable gearing 13, the gearing being arranged like the usual lathe gearing so that the speed of the screw spindle 12 may be varied, depending upon the work to be performed. On the carriage 11 is mounted a suitable chuck 14 of the usual construction, but in which for the usual radially adjustable gripping jaws, are substituted radially adjustable die sections 15, 16, 17, 18. These sections are moved radially by adjusting pins 19 each carrying at its inner end the usual bevel gear meshing with the gear teeth 20 cut on one side of ring 21 on the other side of which are formed the spiral threads 22 which mesh with threads 23 for the purpose of moving the die sections in and out radially to adjust the diameter of the die. The inner ends of these die sections are tapered as shown at 24 in Fig. 4, to permit the desired radial adjustment, and the inner ends of the sections are provided with projections 26, 27, 28, 29 which, when the die sections are assembled, 55 form a thread or helical projection increasing in height and decreasing in pitch toward the finishing end of the die. In the preferred form of the invention as shown herein, the projections of each section of the die constitute longitudinal sections of a continuous thread or helical projection progressively increasing in height and decreasing in pitch, so that when the die is assembled, the projections of the different die sections form 65 such a helical projection.

In the form of apparatus herein shown, a hollow tail shaft 30 is provided extending through a sleeve 31 journaled in tail stock 3, the tail shaft being secured at its inner end by a suitable chuck 32 to the rear end of the tube 8. The purpose of this tail shaft is to produce a positive predetermined twist in the tube being corrugated, and for this purpose the tail shaft is rotated at a speed less than the speed of shaft 4, the difference in speeds being such as to produce the desired twist in the tube while it is being folded. This tail shaft may be rotated by any suitable means to produce this result, and in the present form of apparatus the shaft is provided with a groove 33 in which fits a suitable feather (not shown) projecting inwardly from the sleeve 31 to cause the shaft to rotate with the sleeve and permitting it to move longitudinally through the sleeve. 70 The sleeve is driven in any suitable manner such, for example, as from screw spindle 12 through gearing 34.

The tail shaft is preferably hollow so that the rear end of the mandrel 9 may extend into it; but any suitable arrangement may be used for driving the rear end of the tube in the same direction as the finishing end, but at less speed; in fact, the additional retarding force which is produced by the rotation of the tail shaft at less speed than the rotation of the finishing end of the tube, may be obtained by gripping the rear end of the tube 8 in any suitable manner to retard its rotation, such, for instance, as by a friction grip which will permit it to be rotated but at less speed than it would be rotated if it were held back simply by the friction of the die.

Referring to Figs. 2 and 3, it will be observed that the helical die teeth or projections are so constructed that the advance projection simply initiates in the tube a helical mark or groove along which the tube is to be folded, and by thus starting a groove 110 in the tube it gives it a line of least resistance along which to fold under the twisting force. It will also be noted that the advance convolution of the helical projection marks out along the length of the tube sufficient metal to form the axial sectional configuration of the desired fold in the ultimate product; that is, the distance between points 36 and 37 is equal to the length of the curved out line between points 38 and 39.

By marking out along the tube sufficient metal to form the sectional outline of a fold of the desired depth and pitch, it is possible to form the desired folds according to my invention without appreciably stretching or spinning out the metal, as hereinbefore explained. It will be further observed from inspection of these drawings, that the greatest diameter of the helical groove of the die is the same throughout 130

the length of the groove and is equal to the diameter of the tube to be corrugated. This insures the diameter of the corrugated tube being the same as the original diameter of 5 the tube, since it positively prevents any outward expansion of the tube during the folding process, and the outer surface of the folds may be made to assume an outline depending upon the outline of the grooves between the 10 projections of the die. When a die of this character is used and relative rotation is produced between the tube and the die while the tube is gripped by the die, the friction produced is so great that the tube is twisted, 15 and as the metal of the tube under this twisting force and the relative longitudinal movement between the die and the tube, is drawn through the helical path or grooves in the die, the helical line along which the 20 tube is gripped by the advance convolutions of the die is gathered or drawn together in forming the folds. The friction produced by a corrugating tool or die of this character is so great that sufficient friction is obtained 25 for corrugating tubes of certain sizes without the use of any means for retarding the rear end of the tube or for positively driving it at less speed than the front end to produce a positive twisting force. Tubes 30 as large as 3 inches in diameter and with walls a thirty-second of an inch thick, have been successfully corrugated by such dies without any additional retarding force applied at the rear of the tube, but the application 35 of a retarding force at the rear end of the tube makes it possible to utilize a tool having less friction, and whether or not this be taken advantage of, it produces corrugations of greater uniformity and enables tubes of greater wall thickness to be 40 more readily corrugated.

When it is desired to form tubes of a given size but with greater flexibility and larger radiating surface than is possible 45 with the die shown in Figs. 2 and 3, means may be provided for pressing longitudinally on the folds while they are being formed so as to bend them toward one end of the tube as shown in Figs. 5, 8 and 9. This is 50 done in the form of apparatus herein shown (Fig. 5) by gradually turning the edges of the helical projections longitudinally at the finishing end of the die so as to progressively bend the folds longitudinally as 55 they are being deepened. I have found it preferable to commence this longitudinal turning over or bending of the helical projections at about one and a half convolutions from the finishing end of the die and 60 gradually increasing the longitudinal projection until it is of such depth as to give the desired shape to the ultimate fold. While I have shown these projections with longitudinally bent edges as an integral 65 part of the die sections, obviously they need

not be made integral with the remaining part of the sections. Besides obtaining corrugated tubes of greater flexibility and radiating surface by bending the folds longitudinally as shown in Figs. 5, 8 and 9, the 70 bending of the folds in this manner enables the corrugated tube to be more readily drawn from the mandrel, since the folds, instead of bearing down perpendicularly upon the mandrel, are inclined or so constructed that they will more readily yield when the mandrel is being drawn out. 75

In the drawings herein shown, the mandrel is of such diameter with respect to the setting of the die, that the last tooth of 80 the die folds the tube down upon the mandrel; but if desired, the finishing tooth or convolution need not come down so close to the mandrel, and the twisting of the tube after it leaves the finishing end of the die 85 may be relied upon to finish the folding of the tube down upon the mandrel.

The corrugating or folding of tubes according to my invention by the use of the form of apparatus herein shown for carrying out the invention, is as follows: The tube 8 to be folded is preferably, though not necessarily, drawn down to a taper near its forward end so as to fit the taper of the die, and the tube is then slipped over the 95 mandrel and the mandrel and tube are secured in the chuck 7 in any suitable manner so as to rotate together with the chuck. The hollow tail shaft 30 (when one is used) is then pulled forward through the sleeve 31 100 and after the rear end of the mandrel has been slipped into it, the rear end of the tube 8 is secured in the chuck 32, and the carriage 11 being up at the head of the frame to bring the die in the position shown in 105 Fig. 2, the sections of the die are gradually moved inwardly by turning one of the pins 19 until the helical projection formed by the different projections on the die sections, grips the tube along the tapered portion. 110 If power is now thrown on to rotate shaft 4, the mandrel and front end of the tube will be rotated, and simultaneously therewith the threaded spindle 12 will be rotated to move the carriage along the tube and to rotate the tail shaft and rear end of the tube at a definite predetermined speed less than that at which the forward end of the tube is 115 being rotated so as to positively twist the tube a predetermined definite amount, depending upon the relative rotation between the forward and rear end of the tube. As the die is moved along the tube, the advance point 36 of the helical projection progressively marks or initiates a helical groove in 120 the tube, and the metal marked out by the first convolution of the helical projection, as, for example, the metal between points 36 and 37, is gradually drawn together as the pitch of the helical projection decreases, and 125 130

since the height of the projection progressively increases as the pitch decreases, the metal along the helical line is gradually and progressively pressed inwardly as the lines along which the tube is gripped are drawn together; and as the metal is being gradually forced in by the helical projection, the excess metal, due to the reduction in the diameter along this line, is gradually displaced by the twisting force exerted on the tube, as indicated, by way of illustration, by the direction of the arrows in Fig. 10. This twisting force, as previously stated, not only displaces this metal under the inward pressure so as to permit the deepening of the grooves to the desired extent without wrinkling or rupturing the metal, but the twisting in itself tends to fold the tube helically along the line of least resistance produced by the helical groove initiated in the tube. As the die carriage is moved along the tube, the die progressively marks the tube in this manner and the twisting force is continuously applied as described. The effect of the twisting force in the gradual drawing together of the metal of the tube into helical folds may be illustrated, in a way, by reference to Fig. 11, in which 45 is a rod or mandrel to the end 46 of which is secured a helical spring or piece of spring wire which is wound around the rod with a progressively increasing pitch from the end 46. If it is attempted to draw the convolutions of the spring toward end 46 so as to decrease the pitch of the longer convolutions as shown at the end 46 of the mandrel without rotating the mandrel or the free end of the spring, as the convolutions say at points 47 and 48, are gripped and drawn together, the convolutions of the spring between these points will rise from the mandrel as shown in dotted lines; but by gripping the convolutions at the free end of the spring so as to hold them from rotation, then rotating the rod in the direction shown by the arrow 49 and gradually drawing the convolutions together toward end 46, the spring will be folded down firmly upon the rod in the desired decreased pitch without increasing its diameter and without any tendency to buckle out of the desired form of the spring. During this rotation of the rod the spring will actually slide along and move around the mandrel in a helical line as indicated by the arrows 50. In a somewhat similar manner, when a tube is being folded according to my method of folding tubes, the twisting force applied actually displaces or carries the metal around helically so that the resulting corrugated tube formed under the twisting force is actually slightly longer than the tube would have been if it could have had similar corrugations formed in it without the twisting force.

65 The amount that the tube may be twisted

in forming the folds may be varied in several ways such as by varying the relative rate of rotation of the advance and rear ends of the tube, or by varying the pitch of the die relative to that of screw shaft 12, or the speeds of the shafts 4 and 12.

In practice I have found that it is very important to provide a support for the tube being corrugated, such, for example, as the mandrel. Such a support is an important feature in regulating the action of the twisting force on the folds, and by the regulation of this force, folds of the desired configuration and size may be formed. For example, when the finished folds are brought down firmly upon the support and only sufficient relative rotation between the shafts 4 and 30 is produced to displace the metal as it is being pressed upon by the die, or to bring the folds down upon the support after they leave the die, where the support is of less diameter than the die, the friction between the folds and the support is sufficient to prevent relative rotation between the support and the folds which have been forced firmly into engagement therewith, so that the support will serve to localize the twisting force in the tube by transmitting the force from the chuck to the portion of the tube being folded down upon the support. By reason of this the folds that have been brought firmly into engagement with the support are protected from further effects of the twisting force, so that the tube may be deeply corrugated under the twisting force and the pressure of the die, without crowding together the folds after they have been forced down firmly into engagement with the support. If, however, it is desired to force the folds more or less together to change the sectional configuration of the same, and to decrease their pitch after they have been forced firmly into engagement with the support, this may be done by decreasing the longitudinal travel of the die with relation to the pitch of its helix. I have found that without a suitable support, the tube under the twisting force necessary to deeply corrugate it, will twist up and buckle, since only a very short length of tube can transmit the twisting force necessary to overcome the friction of the die without being distorted; and again the corrugations formed would, under such force, likewise be twisted and distorted out of the desired shape and size.

In Fig. 6 the dotted helical line 52 represents the seam of the original tube which was corrugated, and illustrates the relative amount of twist in the corrugated tube for a given length. If, in corrugating tubing in the shape shown in Fig. 6, the shaft should be driven at 38 revolutions and the tail shaft 30 at 32 revolutions, there would be a difference of 6 revolutions representing 6 complete twists in the tube, and if the pitch

of the screw shaft 12 and the corrugated pipe 8 is $\frac{1}{2}$ inch, and the screw shaft is driven at 38 revolutions a minute, the corrugated tube will have been completely twisted 6 times for 5 every $9\frac{1}{2}$ inches.

Fig. 7 shows the manner in which the folds or corrugations are forced together when the relative diameters of the die and the mandrel are such that there is a clearance 10 between the folds of the tube and the mandrel as the folds leave the die, in which case the twisting force due to the relative rotation of the mandrel with respect to the die, will further twist the corrugated tube 15 until the folds are drawn by the twisting force firmly together, as shown in Fig. 7, or the crowding of the folds along the mandrel may be accomplished in another manner by decreasing the speed of the shaft 12, 20 as previously pointed out.

Fig. 8 shows one form in which tubes may be corrugated with a die having a portion of its projection near the finishing end bent longitudinally somewhat in the manner 25 shown in Fig. 5, but the teeth or projections of the die being so formed that one wall of each fold remains upright while the other wall of the fold is bent in such a manner that each fold overhangs on one side the 30 adjacent groove; whereas, in Fig. 9 the entire fold droops over to one side.

In referring to the helical contour or thread of the tool or die, I have used the terms "helix," "helical projection" and "helical projections" somewhat synonymously and interchangeably, because the projections of the tool or die sections, when assembled, form a continuous helical projection; and in so far as the principle of my invention is concerned, it may be regarded as a unitary solid helical projection, or as composed of a greater or less number of projections than those herein shown. For convenience of description, I have also used the terms "folds" 45 and "each fold" in referring to the corrugated or folded tube, since each convolution of the helically folded tube may be considered as a fold.

While I have shown and described the 50 preferred form of apparatus for carrying out my process, and have described the process in detail in connection with the form of apparatus shown, so as to enable those skilled in the art to more readily understand the invention and practise it with such apparatus, it will be understood that the invention can be carried out by different forms of apparatus from that herein shown and described, and that, in the light of my 55 invention, those skilled in the art may be able to modify or change prior apparatus and the proposed operation of the same so as to enable them to be used for corrugating tubing according to my invention, and I do

not wish to be understood as limiting myself 65 other than as indicated in the appended claims.

I make no claim herein to the apparatus for corrugating tubes, or the product in corrugated tubes, since the apparatus and 70 product form, respectively, the subject-matter of my co-pending applications Serial No. 741,390 and Serial No. 741,388 each filed on even date herewith.

Having thus described my invention, what 75 I claim as new and desire to secure by Letters Patent, is:

1. The method of forming flexible corrugated tubes, which consists in pressing upon a tube along a helical line of decreasing 80 pitch and simultaneously twisting the portion of the tube being pressed upon to displace the excess metal along said line as it is being compressed.

2. The method of forming flexible corrugated tubes, which consists in initiating in a tube a helical groove of less depth and of greater pitch than desired in the ultimate product and deepening the groove and decreasing the pitch by twisting the grooved 90 metal and simultaneously and progressively pressing inwardly on the tube along the helical groove while twisting it so as to displace the excess metal being compressed along the groove in deepening the groove and decreasing its pitch. 95

3. The method of forming flexible corrugated tubes, which consists in progressively initiating a helical groove in the metal of such pitch as to mark out along a tube sufficient metal to form a fold of the desired depth and pitch in the ultimate product without substantial change in wall thickness and simultaneously deepening the groove and decreasing its pitch by continuously 100 twisting the grooved metal and gradually pressing it inwardly while twisting it. 105

4. The method of forming flexible corrugated tubes, which consists in progressively gripping a tube along a helical line of decreasing pitch, the pitch of the advance convolution being such as to mark out along the tube a sufficient length of metal to form an ultimate fold of the desired depth and pitch without substantial change in wall thickness, and twisting the tube and by the aid of such twisting drawing together the gripped metal into helical folds. 110

5. The method of forming flexible corrugated tubes, which consists in progressively 115 forming in a tube a helical groove of less depth and of greater pitch than desired in the ultimate product and progressively increasing the depth of the groove and decreasing its pitch by simultaneously pressing inwardly on the metal along the groove, drawing together its convolutions and twisting it. 120

6. The method of forming flexible corrugated tubes, which consists in progressively initiating in a tube a helical groove of such pitch as to mark out sufficient metal along 5 the tube to form an ultimate fold of the desired depth and pitch without substantial change in wall thickness, and progressively increasing the depth of the groove and decreasing its pitch by simultaneously pressing inwardly on the metal along the groove, 10 drawing together its convolutions and twisting it.
7. The method of forming flexible corrugated tubes, which consists in gripping a 15 tube along a helical line and producing a continuous twisting force therein, and while producing such twisting force progressively and simultaneously drawing together the convolutions of the helical line along which 20 the tube is thus gripped and positively forcing the metal inwardly along said line.
8. The method of forming flexible corrugated tubes, which consists in gripping a tube along a helical line of greater pitch 25 than desired in the ultimate product, and progressively drawing together the convolutions of the helical line along which the tube is gripped and simultaneously therewith progressively forcing the metal along 30 said line inwardly and twisting it to assist in gathering together the helical folds and to move the excess compressed metal along a helical path.
9. The method of forming flexible corrugated tubes, which consists in gripping a tube along a helical line and producing a continuous twisting force therein, and while 35 producing such twisting force progressively and simultaneously drawing together the convolutions of the helical line along which the tube is thus gripped and positively forcing the metal inwardly along said line, and decreasing the pitch of the folds by twisting the metal thus folded.
- 40 10. The method of forming flexible corrugated tubes, which consists in gripping a tube along a helical line and producing a continuous twisting force therein serving to actually twist the metal of the tube, and 45 while producing such twisting force progressively and simultaneously drawing together the convolutions of the helical line along which the tube is thus gripped and positively forcing the metal inwardly along 50 said line, while confining the shell of the tube from outward expansion.
- 55 11. The method of forming flexible corrugated tubes, which consists in progressively gripping a tube along a converging 60 helical line of decreasing pitch and simultaneously and continuously twisting the tube to cause the gripped metal to be gradually drawn together longitudinally of the tube into helical folds.
12. The method of forming flexible corrugated tubes, which consists in producing a twisting force in a tube to twist it helically and contract it longitudinally and simultaneously and progressively initiating a helical groove in the tube to provide a line along which the tube may be folded under the twisting force, and gradually and simultaneously gathering the grooved metal into helical folds. 65
13. The method of forming flexible corrugated tubes, which consists in producing a twisting force in a tube to twist it helically and contract it longitudinally and simultaneously and progressively initiating a helical groove in the tube to provide a line 70 along which the tube may be folded under the twisting force, and gradually pressing inwardly on the tube along said groove and simultaneously gathering the grooved metal into helical folds. 75
14. The method of forming flexible corrugated tubes, which consists in gripping the metal along a helical line of decreasing pitch, and continuously twisting the finishing end of the tube while retarding the rear 80 end so as to cause the gripping metal to be drawn under the twisting force into helical folds of the desired depth and pitch. 85
15. The method of forming flexible corrugated tubes, which consists in rotating the 90 ends of a tube in the same direction at different rates having a constant relation to twist the tube, and while thus twisting the tube, gripping it along a helical line of decreasing pitch to cause the gripped metal 95 to be drawn together under the twisting force into helical folds of the desired depth and pitch. 100
16. The method of forming flexible helically corrugated tubes, which consists in 105 pressing upon the wall of a tube along a helical line and simultaneously rotating the ends of the tube in the same direction at different speeds having a constant relation to twist the tube and cause the metal being 110 pressed upon to be folded into folds having a continuously uniform amount of twist, and protecting the finished folds from distortion by the twisting force. 115
17. The method of forming flexible helically corrugated tubes, which consists in 120 pressing upon the wall of a tube along a helical line and simultaneously rotating the ends of the tube in the same direction at different speeds having a constant relation to each other and to the rate at which the folds are being formed to twist the tube and cause the metal to be folded into helical folds having a uniform pitch and amount of twist. 125
18. The method of forming flexible helically corrugated tubes, which consists in continuously twisting the tube and grip-

ping the twisting portion of the tube along a helical line of decreasing pitch at a progressively shifting short length of the tube in the carrying out of which the gripping means is positively moved continuously along the tube at a uniform rate with respect to the amount of twist being produced in the tube to produce symmetrical folds.

19. The method of forming flexible helically corrugated tubes, which consists in gripping the tube along a helical line of decreasing pitch at a progressively shifting short length thereof and simultaneously producing a twisting force in the tube and localizing the twisting force to the length of tube being folded, in the carrying out of which the gripping means is continuously moved along the tube at a uniform rate with respect to the amount of twist being produced in the tube so as to produce symmetrical folds.

20. The method of forming helically corrugated tubes which consists in progressively gripping the outer surface of a tube along a helical line of decreasing pitch, and producing a twisting force therein sufficient to actually twist the metal of the tube and by the aid of such twisting drawing together the gripped metal into helical folds, and simultaneously with such operation protecting from further twisting the folds which have been formed of the desired pitch.

21. The method of forming flexible corrugated tubes, which consists in progressively gripping the outer surface of a tube along a converging helical line of decreasing pitch and simultaneously and continuously twisting the tube and by the aid of such twisting gradually drawing together the gripped metal and folding it down upon an inner support into helical folds of the desired depth and pitch.

22. The method of forming flexible helically corrugated tubes, which consists in twisting a tube and while twisting it pressing upon it along a helical line to fold the metal helically and draw the folds down upon an inner support serving to prevent the finished folds from being twisted out of their desired shape and to localize the twisting of the metal to the portion of the tube being folded.

23. The method of forming flexible helically corrugated tubes, which consists in twisting a tube and while twisting it pressing upon it along a helical line to fold the metal helically and while thus twisting and pressing upon the metal positively limiting the depth of the folds being formed and protecting the folds thus formed from further effects of the twisting force.

24. The method of forming flexible helically corrugated tubes, which consists in gripping a tube along a helical line at a

progressively shifting short length of the tube and producing a twisting force in the tube to fold the metal helically while localizing the twisting to the portion of the tube being folded, and simultaneously, by means of the gripping means, positively confining and guiding the folds under the gripping pressure and the twisting force, into a predetermined shape.

25. The method of forming helically corrugated tubes, which consists in forming helical folds in a tube and bending said folds over longitudinally to one side of the helical axis.

26. The method of forming helically corrugated tubes, which consists in gradually and simultaneously gathering the metal along the length of the tube into helical folds and bending over a wall of each fold as the fold is being formed.

27. The method of forming helically corrugated tubes, which consists in gradually folding the metal of a tube into helical folds, and bending each fold longitudinally while forming it.

28. The method of forming helically corrugated tubes, which consists in producing an actual twisting of the metal at a progressively shifting short length of the tube and positively guiding the metal being twisted into helical folds and bending each fold longitudinally while forming it.

29. The method of forming flexible corrugated tubes, which consists in progressively gripping a tube along a helical line of decreasing pitch, the pitch of the advance convolution being such as to mark out along the tube a sufficient length of metal to form an ultimate fold of the desired depth and pitch without substantial change in wall thickness, and twisting the tube and by the aid of such twisting drawing together the gripped metal into helical folds, and pressing a wall of each fold over longitudinally while forming the fold.

30. The method of forming flexible corrugated tubes, which consists in pressing upon the metal of a tube along a helical line of decreasing pitch, and twisting and drawing together the metal while pressing upon it.

31. The method of forming flexible helically corrugated tubes, which consists in gripping the metal along a helical line at a progressively shifting short length of the tube and while pressing upon it along said line actually twisting it at said progressively shifting short length.

32. The method of forming flexible helically corrugated tubes, which consists in producing an actual twisting of the metal at a progressively shifting short length of the tube and positively guiding into helical folds the metal being twisted.

33. The method of forming flexible heli-

cally corrugated tubes, which consists in pressing upon the wall of the tube along a helical line and simultaneously producing a twisting force in the tube sufficient to 5 actually twist the metal and localizing the actual twisting of the metal by said force to substantially the length of the tube pressed upon.

In testimony whereof, I have signed my name to this specification, in the presence of 10 two subscribing witnesses.

LOUIS H. BRINKMAN.

Witnesses:

EDWIN SEGER,
SAMUEL M. WARD, JR.

It is hereby certified that in Letters Patent No. 1,120,267, granted December 8, 1914, upon the application of Louis H. Brinkman, of Glen Ridge, New Jersey, for an improvement in "Methods of Corrugating or Folding Tubes," an error appears in the printed specification requiring correction as follows: Page 7, line 91, for the word "gripping" read *gripped*; and that the said Letters Patent should be read with this correction therein that the same may conform to the record of the case in the Patent Office.

Signed and sealed this 25th day of May, A. D., 1915.

[SEAL.]

R. F. WHITEHEAD,

Acting Commissioner of Patents.
